Primary Examiner — Melanie H Tung*Assistant Examiner* — Fitzgerald L Butac(74) *Attorney, Agent, or Firm* — Scarinci Hollenbeck LLC(57) **CLAIM**

The ornamental design for a robot, as shown and described.

DESCRIPTION

FIG. 1 is a perspective view;

FIG. 2 is a front view;

FIG. 3 is a back view;

FIG. 4 is a left side view;

FIG. 5 is a right side view;

FIG. 6 is top view; and,

FIG. 7 is a bottom view.

The “dash-dot” broken line seen in FIG. 7 defines the bounds of the claimed design and forms no part thereof.
